UNITED STATES PATENT OFFICE.

JOHN ROCHE, OF HOBOKEN, NEW JERSEY, ASSIGNOR OF ONE-HALF TO WILLIAM P. VERDON, OF HOBOKEN, NEW JERSEY.

DIMMING HEADLIGHT FOR MOTOR VEHICLES.

Application filed December 8, 1927. Serial No. 238,481.

My invention relates to a new and useful improvement in dimming head lights for motor vehicles, and has for its object to provide a new, simple and effective means for modifying or dimming light rays from an electric lamp so as to avoid the glare heretofore incident to the head lights of motor vehicles, thus rendering the traffic upon crowded thoroughfares less dangerous and less trying upon 10 the eyes of drivers.

Another object of my invention is to so cover the reflector of a head light as to permit the direct rays of the lamp to pass through the coating and be modified in its reflection.

15 A further object of my invention is to provide for modifying the rays of light from the lamp by a suitable translucent covering upon the outer surface of the bulb of said lamp and also to provide for the escape for a certain amount of rays of light through uncoated portions of said bulb and further to provide for varying the amount of unmodified light which may issue through said bulb.

20 A still further object of my invention is to provide for controlling the amount of unmodified light issued from the bulb from the instrument board of the vehicle.

With these and other ends in view, this invention consists in the details of construction 30 and combination of elements hereinafter set forth and then specifically designated by the claims.

In order that those skilled in the art to 35 which this invention appertains may understand how to make and use the same, I will describe its construction in detail, referring by numerals by the accompanying drawings forming a part of this application, in which:

Fig. 1, is a front view of the reflector of 40 a head light containing my improvements, the lens being removed.

Fig. 2, is a central vertical section of Fig. 1, showing the translucent coating upon the reflector and upon a portion of the lamp bulb, 45 and one means of varying the amount of unobstructed light passing from said bulb.

In carrying out my invention, as herein embodied, 10 represents the casing of a motor vehicle head light in which is mounted the reflector 11 and this reflector has a super-imposed layer 12 of a translucent gum-like coating through which, when the rays of light pass to the reflector and are returned there-

from, they are modified to prevent the undue glare which is incident to the reflection of 55 light from an electric lamp, and 13 represents an electric lamp bulb mounted at the center of this reflector and having a super-imposed layer 14 of translucent material through which the rays of light pass from the lamp, 60 thus modifying these rays so as to prevent an intense concentrated glare in front of the head light.

I provide a light regulating shield 15 having a shank 16 which is threaded upon the lamp socket, the body of the shield being such as to close over that portion of the bulb which is not coated; by which arrangement this shield may be rotated upon its axis, which will cause it to move away from or toward the 70 bulb, thereby permitting the outflow of a greater or less amount of light through the transparent portion of the bulb. This provides for increasing or decreasing the intensity of the light passing to the reflector through 75 the super-imposed layer 12, thus giving the user of the head lights any illumination of the road bed which he may desire to meet the varying requirements of motor vehicle traffic.

Of course I do not wish to be limited to the exact details of construction as herein shown, as these may be varied within the limits of the appended claims without departing from the spirit of my invention.

Having thus fully described my invention, what I claim as new and useful is:

1. A device of the kind described including a reflector having a modified light reflecting surface, a lamp positioned centrally of said reflector, said lamp having a translucent front portion and a transparent rear portion, said translucent portion permitting modified light rays to reach the modified light reflecting surface of the reflector and said transparent portion causing unmodified light rays to be projected onto the modified reflecting surface of said reflector, and means to cover a selected proportion of the transparent portion of the lamp to vary the amount of unmodified light rays passing to the modified reflecting surface.

2. A device of the kind disclosed including a reflector having its entire reflecting surface covered with a film of colored light modifying substance, a lamp positioned centrally

of said reflector and having only its front half covered with a colored light modifying substance permitting modified light rays to reach the modified reflecting surface and the, means removably mounted on the transparent portion of the lamp for varying the amount of unmodified light rays passing to said modified reflecting surface. 10

5 rear portion of said lamp being transparent causing unmodified light rays to be projected unto the modified reflecting surface, and In testimony whereof I have hereunto affixed my signature.

JOHN ROCHE.
